FIG. 3

INVENTOR

Richard D. Hill

UNITED STATES PATENT OFFICE.

RICHARD D. HILL, OF WICHITA FALLS, TEXAS, ASSIGNOR OF ONE-THIRD TO JOHN M. SPELLMAN, ESQ., OF DALLAS, TEXAS.

ROTARY SLIP.

Application filed March 15, 1924. Serial No. 699,525.

To all whom it may concern:

Be it known that I, RICHARD D. HILL, a citizen of the United States, and a resident of Wichita Falls, in the county of Wichita 5 and State of Texas, have invented new and useful Improvements in Rotary Slips; and I do declare the following to be a full, clear, and exact description of the invention, such as will enable others skilled in the 10 art to which it appertains to make and use the same.

My invention relates to rotary slips to be used in connection with rotary well drilling, and it is my principal object to provide slips 15 that will hold drill stem securely and not cut the same, the slips being specially adapted for use with a tool joint having notches on the bottom and a circumferential groove intermediate its ends, the said tool joint being 20 described and claimed in another application.

A further object is to provide rotary slips of this nature having teeth in the top thereof to prevent circumferential slippage of the 25 drill stem in the slips.

Further objects and advantages will be apparent as the invention is more fully disclosed.

With the foregoing in view, the invention 30 resides in the novel subject matter herein-after described and claimed, the description being supplemented by the accompanying drawing, wherein,

Figure 1 is a partly sectioned side view 35 showing the slips assembled in a rotary drilling table.

Figure 2 is a top view showing the slips assembled in a rotary drilling table.

Figure 3 is a perspective view illustrating 40 the manner of operation.

Figure 4 is a perspective view of one of the slips with the teeth removed.

Figure 5 is a perspective view of one of the slip teeth.

Figure 6 is a perspective view of the tool 45 joint that is specially adapted for use in connection with this type of slips.

The invention comprises a pair of half-round members 1 and 1^a, which are placed in the tapered aperture of the rotary drilling table 2, as shown, each of the half-round members having an exteriorly disposed flange 3 at the top thereof, and a projection disposed centrally exteriorly on the said flange. 4 and 55 4^a are oblong blocks attached to the rotary

drilling table 2 with bolts as shown at 5 and 5^a. 6, 6^a, 6^b and 6^c are connecting links pivoted at each end thereof and extending between the oblong blocks 4 and 4^a and the projection on the flange 4 of the half-round 60 members 1 and 1^a. The connecting links 6^a and 6^b are provided with removable handles 7 and 7^a for the purpose hereinafter described. It will be noted that the exterior of the half-round members 1 and 1^a is tapered 65 to conform with the tapered aperture of the rotary drilling table 2. The lower ends of the half round members are beveled exteriorly to provide a clearance when being inserted in the rotary table. The interior 70 of both half-round members is beveled at the bottom thereof to guide the tool joints on the drill stem as the same is being removed from the hole. The upper portion of each half-round member is provided with 75 a pair of vertical dove tail grooves. 8 is a dove tail tooth of proper size to slide into the dove tail grooves of the half-round members 1 and 1^a, thus providing means for replacing the teeth as they become worn. The 80 top of the dove tail tooth 8 on the small side is beveled, making the center pointed to engage the notches in the tool joint, as shown in Figure 6.

In operation the slips when disposed in the position as shown in Figure 3 may be pushed into the rotary drilling table aperture or they may be inserted by raising the handles 7 and 7^a. To remove the slips from the rotary drilling table aperture the 90 handles 7 and 7^a are moved to the position as shown in Figure 3. When the slips are in the rotary table aperture the notches on the tool joint which is attached to the drill stem mesh with the dove tail teeth 8 in the 95 half-round members 1 and 1^a, when the said drill stem is lowered, thus preventing circumferential slippage of the tool joint and drill stem when the rotary drilling table 2 is being rotated.

Rotary slips involving this principle may be used without the teeth 8, making the interior of the half-round members smooth, and eliminating the notches in the lower end of the tool joint, it is then necessary, however, to use a wrench on the said tool joint to prevent circumferential slippage when the rotary table is being rotated.

It is believed from the foregoing description the nature and advantages of the in- 110

vention will be readily apparent, however, I wish to indicate clearly that I do not limit myself to the specific construction herein shown and described, and that such other changes may be resorted to, when desired, as fall within the scope of what is herein claimed.

What I claim is:

1. In a rotary drilling table, a pair of conically shaped semi-circular members 10 removably mounted therein and adapted to encircle a drill stem; a plurality of tooth members slidably mounted in grooves in the inner face of said semi-circular members and projecting inwardly therefrom to form pockets between the same and around the circumfer-

ence of said inner face, said pockets being open at the top and adapted to receive co-acting lugs therein formed on the drill stem.

2. In a rotary drilling table, a pair of 20 conically shaped semi-circular members removably mounted thereon by means of outwardly projecting lugs, levers connected to said lugs and to other lugs on the face of the table, said semi-circular members having grooves in their inner faces, teeth of relatively soft material removably mounted in said grooves, coacting lugs removably secured to the stem of a drill and adapted to engage the teeth set in the semi-circular members.

RICHARD D. HILL.
